(57) **CLAIM**

The ornamental design for a corner piece for shipping container as shown and described.

DESCRIPTION

1. Corner piece for shipping container

1.1: Front

1.2: Back

1.3: Left

1.4: Right

1.5: Top

1.6: Bottom

1.7: Perspective

1.8: Perspective

1.9: A-A cross-sectional view

1.10: B-B cross-sectional view

The characteristic features of the design lie in the shape.
